UNITED STATES PATENT OFFICE.

EDWIN M. CHAFFEE, OF PROVIDENCE, RHODE ISLAND.

IMPROVED APPARATUS FOR COATING AND FLOCKING CLOTH.

Specification forming part of Letters Patent No. 44,281, dated September 20, 1861.

To all whom it may concern:

Be it known that I, EDWIN M. CHAFFEE, of the city and county of Providence, State of Rhode Island, have invented a new and Improved Machine for Coating and Flocking Cloth, &c.; and I do hereby declare that the following is a full, clear, and exact description thereof, which will enable those skilled in the art to make and use the same, reference being had to the accompanying drawings, forming part this specification, in which—

Figure 1 represents a longitudinal vertical section of this invention. Fig. 2 is a side elevation of the same. Fig 3 is an end view of the same.

Similar letters of reference indicate corresponding parts.

The object of this invention is to coat cloth or textile fabrics in pieces one thousand (more or less) yards long by machinery which applies the requisite coat of water-proof or other composition or varnish and the flocks, if desired, and at the same time conveys the cloth to a drying-room, and hangs it in folds upon sticks or slats automatically. The long pieces of cloth are made up of shorter ones, cemented or sewed together as for calendering.

The process of coating is effected while the cloth is being conveyed to the drying-room, and the machine at the same time delivers a series of newly-arranged lattice-frames, which are supplied to it at suitable intervals, and upon the slats or rounds of these frames the cloth is deposited in folds, four or more yards upon each slat, according to the height of the room.

The cloth to be coated, varnished, or flocked is unwound from a roller, A, which has its bearings in a frame, B, of wood, or any other suitable material, and which is situated in the center of an imaginary rectangular scroll of a somewhat irregular form. From said roller the cloth passes down under a roller, C, situated in the first corner of the scroll, and provided with a friction-pulley, C', and strap *a* outside the frame B, to retard its motion, which it receives from the cloth in passing. The cloth then passes upward to the next corner of the scroll, which is occupied by a bar, D, instead of a roller, and the friction on this bar still further increases the tension of the cloth. From the bar D the cloth passes under a knife, doctor, or scraper, E, and before this doctor

the water-proof or other composition is placed, and as the cloth moves along under the doctor enough of the composition is left upon it to form one coating. Behind this knife and within a few inches of it is a supporting-roll, F, the upper surface of which is above the level of the edge of the doctor, whereby the cloth is strained hard up against said edge, in order to equalize the thickness of the coating, and to spread the water-proof, or other composition evenly on its whole surface. From the roller F the cloth continues on in a horizontal direction beneath the flock-sifting box F', and over the first carrying-roller, G, which is driven by a belt, b, extending from the pulley e over the pulley d on the end of the shaft of said roller. Above and resting upon this roller is a pressure-roller, H, between which both cloth and flock pass when flock-cloth is to be manufactured, and it must be remarked that this roller is only used for flocking. The cloth then passes downward, and under the carrying-roller, I, the axle of which has its bearings in the lower part of the frame B, and which receives its motion by a belt, e, passing over pulley f, g, as clearly shown in Fig. 2 of the drawings. From the roller I the cloth passes in a horizontal direction, or nearly so, to the carrying-roller J, the axle of which forms the driving-shaft, by which motion is imparted to the various rollers. After passing through under roller J the cloth passes upward, and over the roller K, thence in a horizontal direction to the delivery-roller L, over which it passes and descends to and between the slats of the lattice-frame M.

By referring to Fig. 1 of the drawings it will be noticed that the cloth, which is represented in red outlines, passes over the several rollers without having its coated surface come in contact with either of them, and by the action of the first roller C and bar D the requisite tension is imparted to the cloth for the operation. The lattice-frame M rolls on castors upon a track, M', supported a short distance below the upper floor of the drying-room, and in the working-machine one of these frames after the other is removed out of it and into the drying room through a narrow opening, which divides the machine from said drying-room.

An automatic intermittent motion is imparted to each frame by two long pins, h, pro-

jecting from the revolving shaft *i*. These pins catch successively behind the several slats commencing with the first and move the frame gradually to let fall two toothed or rough surface-wheels, *j*, which catch over the edges of the cloth and cause the same to descend between the next succeeding slats or rounds. These two toothed wheels *j* are supported upon arms *k*, which are connected to short arms *l* by a limited flexible joint, or in any other convenient manner. Said short arms have square holes through them to fit upon a square rock-shaft, *m*, so that said arms, with the wheels *j*, can be readily adjusted to the width of the cloth to be coated. A lever, *n*, projects from said rock-shaft, and as the lattice-frame is pushed along by the action of the pins *h*, projecting from the revolving shaft *i*, the slats coming in contact with the lever *n* raise the same, and thereby the rock-shaft *m* is turned, and the arms, with the wheels *j*, are raised. When the lever *n* passes the slat, both wheels drop with it, and by means of the jointed arms *k l* they (the wheels) adjust themselves to crooked or oblique slats, and thereby they are enabled to act upon the cloth with the desired effect under all circumstances. The tension and all the carrying rollers are covered with emery, or their surface is otherwise made rough. The surface of the last or delivery roller ought to be made more rough or adhesive than the others, covering it with card-clothing, and the axle of said roller has its bearings on an extension of the frame *B* directly over the rock-shaft *m*, said extension being made to pass through the opening in the partition which separates the machine from the drying-room in such a manner as to allow the cloth to drop beyond the partition into the drying-room.

In order to permit the cloth to fall several feet before it reaches the slats, the delivery-roller ought to be situated somewhat higher than the top of the drying-room, or, if possible,

the machine ought to be made of such a height that the cloth will drop through one floor to the lattice-frames below, while the said frames may be moved by machinery in the same story with them.

The frames may be fed to the machine in any suitable manner, either one at a time by the tender, or by supplying a large number at a time, piled up one above the other, and so situated that the bottom frame is gradually moved from beneath the pile.

In practice the frame *A* is placed on a truck, so that it can be readily moved from one place to another. This truck is not represented in the drawings.

I claim as new and desire to secure by Letters Patent—

1. The rollers *A, C, F, G, I, J, K, L*, and doctor *E*, or their equivalents, arranged in relation to each other and to the cloth substantially in the manner herein described, so that long pieces of cloth can be coated and conveyed to the drying-room without bringing the face or varnished side of the cloth in contact with the rollers or anything else except the edge of the doctor.

2. The employment or use of two toothed wheels, *j*, arranged substantially as herein specified to check the fall of the cloth at the desired intervals.

3. The jointed arms *k l*, in combination with the toothed wheels *j*, to act substantially as and for the purpose set forth.

4. The combination of the rock-shaft *m*, adjustable arms *k l*, and wheels *j*, substantially as herein specified, to insure the simultaneous catching of both edges of the cloth.

5. The employment of the lattice-frames *M* substantially in the manner set forth for the purpose of supporting the cloth while in the drying-room.

EDWIN M. CHAFFEE.
